NO. 36,682.

Patented December 22, 1903.

UNITED STATES PATENT OFFICE.

EDWARD B. KINGMAN, OF LEOMINSTER, MASSACHUSETTS.

DESIGN FOR A COMB.

SPECIFICATION forming part of Design No. 36,682, dated December 22, 1903.

Application filed October 24, 1903. Serial No. 178,447. Term of patent 7 years.

To all whom it may concern:

Be it known that I, EDWARD B. KINGMAN, a citizen of the United States, residing at Leominster, in the county of Worcester and State of Massachusetts, have invented a new, original, and ornamental Design for a Comb, of which the following is a specification.

In the accompanying drawing the figure is a perspective view of a comb embodying my design.

Having illustrated my design, what I claim

as new, and desire to secure by Letters Patent, is—

The ornamental design for a comb as herein shown.

In testimony whereof I have hereunto set my hand in the presence of two subscribing witnesses.

EDWARD B. KINGMAN.
